UNITED STATES PATENT OFFICE.

MICHAEL SOSNOSKI, OF KINDE, MICHIGAN.

STOVE.

No. 839,663.

Specification of Letters Patent.

Patented Dec. 25, 1906.

Application filed February 24, 1905. Serial No. 247,203.

To all whom it may concern:

Be it known that I, MICHAEL SOSNOSKI, a citizen of the United States, residing at Kinde, in the county of Huron and State of Michigan, have invented certain new and useful Improvements in Stoves; and I do declare the following to be a full, clear, and exact description of the invention, such as will enable others skilled in the art to which it appertains to make and use the same.

My invention relates to improvements in stoves adapted for heating and cooking purposes.

The object of the invention is to improve and simplify the construction of stoves of this character, and thereby render the same more durable and efficient and less expensive to manufacture.

With the above and other objects in view the invention consists of certain novel features of construction, combination, and arrangement of parts, as will be hereinafter described and claimed.

In the accompanying drawing I have shown a vertical front-to-rear sectional view through a heating-stove embodying my improvements.

Referring to the drawing by numeral, 1 denotes the casing of my improved heating-stove, which has in its lower portion a chamber divided by a grate 2 to form a fire-box 3 and an ash pit or box 4 and its upper portion formed with a smoke-chamber or compartment 5, which communicates with a smoke pipe or flue 6. The fire box or chamber 3 and the smoke-chamber 5 are in communication through a plurality of vertical smoke pipes or flues 7, which extend through the intermediate portion of the casing 1 between the said chambers. This intermediate chamber or space is filled with sand or other material 9, which is a poor conductor of heat, so that when it is once hot it will retain its heat for a considerable length of time. The pipes or flues 7 have their ends projecting through and secured in horizontal partition-plates 10^a, which are suitably secured within the casing 1 and separate the interior of the latter into its upper, lower, and intermediate chambers or compartments. Between the partition-plate 10^a and the top of the fire-box 3 is provided an air-space 10^b, which permits the smoke and heat to enter the pipes 7 and pass therethrough and into the smoke-compartment 5. The usual doors 11 and 12 are provided in front of the chambers 3 4.

To the top of the casing 1 and over the smoke-compartment 5 is arranged a removable cover 20, which permits of the pipes and said smoke-compartment being cleaned of soot and the like, which may be forced down through the pipes and into the compartment 3 and thence through the grate-bars 2 and into the ash-pan 4. The cover is provided with pot-openings, which are closed by lids 13.

The operation and advantages of the invention will be readily seen from the foregoing description. The heat from the fire on the grate 2 as it passes upwardly through the flues 7 will quickly heat the sand or other material 9 in the space around said flues, so that the stove will retain a considerable amount of heat after the fire dies down or goes out. Owing to the fact that the material 9 retains its heat for a considerable period, a material saving in fuel is effected by the use of the invention, since it is unnecessary to supply fuel as frequently as in the ordinary heating-stove.

I wish it to be understood that by my construction of stove the heating of cooking-utensils is quickly accomplished when the same are placed in position on the smoke-chamber. The products of combustion coming from the flues of the stove and traveling toward the exit-flue serves to produce the quick heating effect upon the utensils.

Various changes in the form, proportion, and the minor details of construction may be resorted to without departing from the principle or sacrificing any of the advantages of this invention.

Having thus described my invention, what I claim as new, and desire to secure by Letters Patent, is—

In a stove, the combination of the casing, a removable cover therefor, said cover being provided with pot-openings and closing means, said casing being divided by horizontal partitions into an upper smoke-compartment and a lower combustion-chamber and an intermediate heat-radiating chamber, and a plurality of flues providing communication between said smoke-chamber and said combustion-chamber, said heating-chamber being filled with sand or like heat-absorbing material, substantially as described.

MICHAEL SOSNOSKI.
